PROCESS FOR THE MANUFACTURE OF LUBRICATING OILS

Original Filed May 5, 1932

UNITED STATES PATENT OFFICE

2,112,350

PROCESS FOR THE MANUFACTURE OF
LUBRICATING OILS

John E. Schulze, Chicago, Ill., assignor, by
mesne assignments, to Red River Refining
Company, Chicago, Ill., a corporation of Dela-
ware

Original application May 5, 1932, Serial No.
609,508. Divided and this application June 4,
1937, Serial No. 146,496

4 Claims. (Cl. 196—83)

This invention relates generally to processes for the manufacture of lubricating oils; and in particular it relates to the manufacture of lubricating oils by straight overhead distillation under high vacuum, that is, under very low absolute pressure. However, the invention is not restricted to distillation of lubricating oils under vacuum, but it is of greatest present utility in that field which will therefore be more particularly referred

10 to in explaining the principles of the invention.

In prior copending application Serial No. 609,508, filed May 5, 1932, of which the present application is a division, this applicant has disclosed and claimed a novel process of manufacturing high grade lubricating oils directly by straight overhead distillation under high vacuum, the distillates thus obtained requiring no acid treatment or filtration to render them finished high grade lubricating oils of good color and stability. The complete process of said prior application comprises generally two principal stages or phases:

In the first stage, there is effected a relatively quick separation of lubricating oil components from the heavier components of a given crude mineral oil material or charging stock by a continuous procedure which includes rapidly heating the crude material to temperatures sufficiently high to vaporize all the desired lubricating oil components under absolute pressure on the order of 50 millimeters of mercury or lower, vaporizing such components at such low absolute pressure, and condensing them under such low pressure as one or more lubricating oil distillates substantially free of tarry and other heavier constituents of the crude starting material employed, as well as from nearly all of the lighter constituents thereof. The lubricating oil distillates thus obtained by quick separation, while superior in some respects to those heretofore obtainable by comparable procedure, are nevertheless characterized by a small content of unstabilizing constituents, and they are not the finished, stable lubricating oils desired. Said distillates are employed, either singly or together, as high grade charging stock in the second stage or phase of the complete process of said prior application.

In the second stage or phase of the complete process of said prior application, the quickly separated and unfinished lubricating oil distillates are subjected, either singly or in mixtures of two or more, to redistillation by batch or discontinuous distillation in which vaporization and subsequent condensation of the lubricating oil constituents is effected under absolute pressures not

exceeding, and most desirably materially below, 25 millimeters of mercury, and at temperatures increasing only very gradually and uniformly, the lubricating oil constituents being thus progressively vaporized in the order of their boiling points and obtained as lubricating oil distillates requiring no acid treatment or filtration to render them finished marketable lubricating oils of good color and stability.

The process of the present invention is a part 10 of the complete process disclosed in said prior application and is directed more particularly to novel features of procedure forming a part of the second stage or phase of said complete process.

An object of this invention is to provide a 15 method or process of recharging a distillation unit or system of the type used in practicing the second phase of the aforesaid process whereby it is not necessary to shut the unit down, or release the vacuum, or clean out the still, before 20 introducing another charge to be run, thus not only saving time, but minimizing heat losses.

Other objects and advantages of the invention will become apparent as the description proceeds.

In order to afford a full understanding of the 25 principles of the invention, a typical practical embodiment thereof will now be described in detail in connection with the accompanying drawing which illustrates more or less diagrammatically and to some extent in the form of a flow 30 sheet, a typical distillation unit or plant wherein the process can be effectively carried out, the principal apparatus or equipment parts being shown in side elevation, with portions broken away to disclose certain structural details.

Referring to the drawing, in utilizing the apparatus system there illustrated in practicing the distilling process of this invention, the distillation, although essentially batch or discontinuous in character so far as the nature of the distillation itself is concerned, is nevertheless semi-continuous from the standpoint of plant manipulation. That is to say, although the lubricating oil components are vaporized in the order of their respective boiling points, which is characteristic 40 of batch distillation, the arrangement of the apparatus is such that, after running a given charge down to a residue or bottoms of, say, 5 to 6 per cent, it is not necessary to shut the unit down, or release the vacuum, or clean out the still, before 45 introducing another charge to be run. This is a point of great practical advantage as can readily be seen.

Generally described, the distillation unit, in the specific form here illustrated, comprises a 55

relatively large capacity vaporizer 110 adapted to contain a suitably large volume of the oil to be processed, in a body having an extensive free upper surface to facilitate rapid vaporization. 5 This oil may be one or more of the lubricating oil distillates obtained from the first stage or phase of the complete process of said prior application aforesaid. The vaporizer, which in this instance takes the form of a shell still, is surmounted by 10 a reflux fractionating tower 111 containing fractionating elements 112. These should most desirably be of such character that resistance to vapor flow is reduced to the utmost possible minimum consistent with sufficiently intimate and 15 prolonged contact between the counterflowing vapor and liquid to ensure adequate fractionation and clean separation of impurities from the desired lubricating oil distillate under the conditions of operation. Liquid reflux is delivered to 20 the top of the series of annular plates 112 by distributor 123^a, the liquid dropping from one plate to the next lower one in filming downwardly over the plate surfaces. By means of 25 curved vanes (not shown) associated with said plates, the ascending vapors are given a whirling movement and are also alternately divided into three passes or streams and reunited into a single stream, as they ascend.

In order to reduce to a minimum any possibility of locally overheating and thus cracking the oil to be run, the vaporizer 110 is not itself heated by contact with flame or hot furnace gases, but the oil to be processed is heated by continuous 30 passage through a pipe still 113, oil being continuously discharged into the vaporizer through line 114 and withdrawn therefrom through line 115 by a centrifugal circulating pump 116 and returned through line 117 to the pipe still for further heating to progressively higher temperatures. 35 The oil passes through the tubes of the pipe still heater at high velocity (e. g. 6 to 8 feet per second) and in a stage of extreme turbulence, thereby practically eliminating any chance of locally overheating and cracking portions of the oil being processed. In order to permit very rapid circulation of a large volume of oil per minute through the pipe still heater and vaporizer the pipe still may desirably be of what is known as 40 multi-pass construction, four passes being indicated at 113^a for the convection bank of tubes and at 113^b for the radiant bank, the several passes being connected in parallel by suitable headers in a known manner. Such an arrangement, together with the ample size of the circulating connections 114, 115, 117, and high operating capacity of pump 116, permits circulation of the oil through the system at the rate of approximately 650 gallons per minute where, in a typical instance, the total initial charge to the 45 system is 21,000 gallons. Generally speaking, circulation of the charge through the system, throughout the distillation, at a per minute rate of about 2 to 4 per cent of the volume of the initial charge of material to the unit, is desirable 50 in practice. Since the volume of the charge in the unit decreases to a residue of say, 5 to 6 per cent, the circulating rate, in terms of the proportion of the charge at later stages, increases greatly as the distillation proceeds.

55 In conducting the distillation with the aid of the system illustrated, feed stock is charged from the charging tank 118 into the system through 120 in a manner to be described in greater detail present. The normal charging level in vaporizer 75 110 is indicated at 119. With the centrifugal

circulating pump in operation, the oil is circulated rapidly through the system in closed circuit, as previously described. The rate of circulation may be observed by means of a suitable flow meter 122 interposed at any convenient point in the circulating lines connecting the heater and the shell still vaporizer. The pipe still heater, in the present example, may be of sufficient capacity (i. e. heating surface area) to raise the temperature of the oil in the shell still approximately 70° F. per hour, and during the initial heating up of the charge, the pipe still heater may be fired at this rate; so that within a period of from 3 to 5 hours, depending on the type of charge being run and other factors, the oil is heated to its initial boiling point. It may be stated that prior to running the charging stock into the vaporizer, it is desirable to treat it with approximately 0.2 per cent by volume of a neutralizing agent such as caustic soda of about 40° Baumé strength, this neutralizing solution being thoroughly mixed with the charging stock. 10

The system comprising the shell still, the fractionating tower, the reflux condenser 123, and final condenser 124, is held under high vacuum 15 throughout the entire distillation of the lubricating fractions by powerful exhausting means which pull all fixed gas and uncondensed vapor out of the system at high velocity through large-diameter offtake 125. In a typical instance, the absolute pressure in line 125 at the outlet of condenser 124, may be 3 millimeters of mercury, while in the vapor space above the charge in shell still 110 it may be 5 to 6 millimeters, a loss of only 2 to 3 millimeters in vacuum. Any suitable 20 exhausting means of sufficient capacity may be used for this purpose, but in practice it is found practical in this instance to use a 3-stage 25 ejector equipment, such as that indicated generally at 126, or a 3-stage reciprocating Worthington pump especially developed for this purpose. The tail water from operation of the ejector equipment, together with that which has been used for cooling the condensers 123, 124, may be carried off through water line 127 and further 30 utilized to cool the finished lubricating oil distillate, as will presently appear. By-pass 128 is provided in the water-cooling system of condensers 123, 124, together with controlling valves 129, 130, whereby the operation of reflux condenser 35 123 can be regulated and controlled to best advantage. 40

As soon as the temperature of initial vaporization is reached in the shell still, the rate of firing of the pipe still heater is controlled to conform with the rate of distillation desired. In a typical instance, where the initial charge consists of the combined lubricating distillates obtained from tower 11 of the primary system of said prior application aforesaid, vaporization of 45 relatively light products begins at around 350° to 360° F., and the rate of firing is thereafter so regulated as greatly to reduce the rate at which the temperature of the oil increases, especially 50 during the distillation of the lubricating oil fractions proper, which may be taken to begin when the stream coming over shows a viscosity of 50 to 60 seconds Saybolt (at 100° F.). The temperature of the charge at this point is ordinarily about 375° to 400° F. From then on until the 55 heaviest lubricating oil fractions have been distilled over, which usually requires around 12 to 14 hours in accordance with the present process, the temperature of the charge is raised very slowly and at a substantially uniform rate to a 60

final distillation temperature of about 560° to 575° F., and not exceeding 600° F. as a maximum. The residue of 5 or 6 per cent, to which the charge is run down, is a very heavy high grade lubricating stock which may be accumulated and re-run by batch distillation, yielding, directly, overhead distillates as finished high grade lubricating oils of good color and stability, with viscosities as high as 110 seconds Saybolt (at 212° F.).

10 Distillation in the manner just described means a temperature rise approximating 150° to 200° F. during 12 to 14 hours of distillation, which is an average rise of less than 0.25° F. per minute or 15° F. per hour. It may be stated that, in practicing the present process, the rate of temperature increase during distillation should not average more than 0.5° per minute at the most.

The discharge from the pipe still heater to the shell still is controlled by a valve 114* in such 20 manner that a slight positive back pressure (e. g. 5 lbs.) is maintained on the oil to minimize vaporization in the tubes of the pipe still heater. After 25 entering the shell still, the line 114 bends downwardly as shown and terminates in a discharge header 130* extending longitudinally of the still and close to the bottom thereof. This discharge header is provided throughout its length with numerous small diameter discharge openings 131 whose total area may desirably be less than the 30 cross-sectional area of the discharge header. This restriction of discharge opening area permits the discharge of the hot oil from the pipe still heater at very high velocity into the lower part of the shell still in many small jets, thus constantly 35 maintaining the body of oil in the shell still in highly turbulent condition and ensuring substantial uniformity of temperature throughout said body. The velocity of the oil at the point of discharge through the small openings 131 is on 40 the order of about 30 feet per second. This provision is of great importance in increasing the efficiency and uniformity of vaporization at the extremely low rate of temperature increase above referred to, thus further favoring uniformity in 45 composition (narrow cut) of the vapors evolved during a given period of time, say several minutes, a fact which, in spite of the very low pressure drop through the fractionator and condenser, as already pointed out, makes for relatively high 50 efficiency in the subsequent fractionation of said vapors and clean separation from the lubricating distillate of the small quantity of relatively volatile malodorous and unstabilizing contaminants included therewith.

55 The vapors rising from the oil in the shell still pass through the large diameter vapor oftake 132 into the fractionating tower and through the entrainment separator 133 located in the base thereof. The vapors then pass upwardly through 60 the system of fractionating plates or trays 112, previously referred to.

The vapor temperature at the top or outlet of reflux condenser 123 is carefully regulated and controlled throughout the distillation in such 65 manner that no condensation of malodorous or unstabilizing products, which are relatively low boiling as compared to the lubricating constituents of the distillation vapors, can occur in the reflux condenser. That is to say, care is taken throughout the distillation to so adjust the water cooling of reflux condenser 123 that the temperature of the uncondensed vapors and gases leaving the same is always high enough to ensure that, at any given time, said vapors include not only 70 those of the aforesaid malodorous and unstabi-

lizing constituents, but also a small proportion of vapors of the considerably higher boiling lubricating constituents then coming over.

Vapors escaping condensation in reflux condenser 123 pass into condenser 124 where they are cooled to a much lower temperature sufficiently low to compel most of the residual vapors to condense. This condensate, which is of unpleasant odor and unstable, is led away through line 134 and look box 135 to tank 136.

The lubricating oil distillate condensed in the tower 111 is led away in side stream from collecting plate 137 through line 138 to constant level seal tank 139. The operation of the fractionating system is so regulated and controlled 15 that the lubricating distillate leaving the tower at any given time is very hot, being practically at its point of initial vaporization. During the greater part of the distillation, the temperature at which it leaves the column or tower is not more 20 than 50 to 60 degrees Fahrenheit below that of the vapors entering the base of the column, and only near the commencement of the distillation is it sometimes as much as 100 degrees below that of the vapors entering the column. This aids 25 greatly in preventing absorption of malodorous constituents from the distillation vapors by the condensate while it remains in the tower; and the possibility of absorption is still further minimized by the maintenance of the extremely high 30 vacuum on the hot condensate even after it leaves the column, thus ensuring withdrawal therefrom of even minute traces of such volatile contaminants. The condensate is withdrawn through line 140 and cooler 141 by pump 142, 35 which then pumps it through line 143 to storage. Line 143 may be provided with sight glass 144 and meter 145, as shown. The lubricating oil cooler 141 may utilize as cooling medium the water discharged through line 127 from the ejector system and condensers at the top of the tower. The operation of lubricating oil pump 142 is automatically regulated by float control device 146, as indicated.

The lubricating oil distillate going to storage 45 through line 143 is the desired final product of the process. When the initial charge is one or more of the unfinished lubricating oil distillates obtained from the first stage or phase of the complete process of said prior application, or any 50 similar charging stock, the product obtained is sweet, stable, finished lubricating oil, of excellent color, resulting directly from straight overhead distillation and requiring no further refining or purifying as by acid treatment and/or filtration. 55 Its particular specifications as to viscosity, boiling range, etc. depend, of course, upon the character of the charging stock used.

The procedure thus far described is typical of the second stage or phase of the complete process 60 disclosed and claimed in said prior application Serial No. 609,508 aforesaid. The process of the present application has to do with that part of the second stage or phase of the aforesaid process whereby the unit may be recharged after running a given charge down to a desired point, without having to shut the unit down, or release the vacuum, or clean out the still, so that the operation of the unit may be semi-continuous in the sense already explained hereinabove.

70 Referring again to the drawing, a stand-by pump 147, which may desirably be steam operated, serves in the capacity of a residue pump when a distillation run or cycle is completed, and also serves to some extent as a charging pump 75

in such manner that the operation of the unit may be semi-continuous, as just mentioned. When a given still charge has been distilled off until a residue of about 6% remains in the shell still, firing of the pipe still heater is discontinued, centrifugal circulating pump 116 is stopped, valve 152 is closed, and circulation of the aforesaid residue is continued at a reduced rate by means of the steam stand-by pump 147, which is arranged in parallel with pump 116 by valved suction and discharge connections 147^a and 147^b, respectively, the valves in these connections having been opened for the purpose. While the described distillation has been going on, a fresh supply of charging stock has been prepared for running and has been placed in the charging tank 118. When the steam stand-by pump has been operating for some time as just described and the stream of lubricating oil condensate flowing from tower 111 through line 138 has ceased, valve 148 in discharge or delivery line 114 from the pipe still heater is closed, and valves 148 and 149 in residue discharge line 150 are opened, thus causing the hot residue to be pumped from the system through residue cooler 151 to storage. Knowing the actual quantity of residue remaining in the system at the end of the distillation, and knowing the capacity of the steam stand-by pump 147 or observing the rate of flow of the residue as indicated by flow meter 122, an operator can determine the exact time when all of the residue has been removed from the shell still. At this time, the suction valve 152 in line 113 leading from the shell still remaining closed the valve 153 in line 120 leading from the still charging tank 118 is opened and the valve in line 147^a is closed, so that the steam stand-by pump then draws fresh charge from the tank through branch line 154 in which valve 155 has been opened for the purpose. The stand-by pump continues to operate until the remaining portion of the residue, which is thus forced through the pipe still ahead of the fresh charge from tank 118, is entirely removed from the system, whereupon valve 148 in the heater discharge line 114 is opened, and valve 149 in the residue discharge line 150 is closed. The proper time for effecting this operation is readily determined from a knowledge of the capacity of the tubes in the pipe still heater and the transfer lines, and the rate at which the steam stand-by pump is operated. A further guide is afforded by noting the temperature drop which suddenly occurs at the outlet in the pipe still heater as the last of the hot residue leaves it. Shortly after the first portion of the fresh charge reaches the shell still, the steam stand-by pump 147 is shut down, the valves in lines 147^a and 147^b are closed, and the centrifugal circulating pump is started to complete the charging of the system with fresh lubricating oil distillate stock to be run; valve 121 in the suction connection of the pump to the charging tank 118 being opened and remaining open until the charging operation is finished, whereupon it is closed and valve 152 is opened again. In the meantime firing of the pipe-still has been resumed.

In the particular installation here illustrated, the discharge side of stand-by pump 147 is also connected by valved line 147^b to discharge line 150, whereby the pump may draw oil from the shell still through line 147^a and discharge it directly into line 150, which may be necessary or desirable upon occasion.

The manipulation of the unit to render its operation virtually semi-continuous may of course

be accomplished in other ways than that described in specific detail hereinabove, such description being given merely by way of concrete example for purposes of explanation. This method of procedure is very advantageous because it renders operation of the distillation unit materially more economical and efficient. Since the shell still, fractionating tower, pipe still heater and all lines connecting the heater with the shell still are insulated, the whole system which is at a temperature well above 500° F. at the end of the distillation, retains a large amount of heat which is thus conserved and utilized to impart a rise in temperature to the fresh charging stock amounting to 70°-80° F. before firing of the pipe still heater is begun. Also, the interval during which the fresh charge is being heated up to initial boiling point for the next distillation is reduced by about one hour as compared to the time required to heat a fresh charge up to the same temperature in a cold unit.

Seal tank 139 has a pressure balancing connection 139^a to tower 111, as shown. Seal tank 138 requires a similar pressure balancing connection unless, as in the illustrated installation, it is located far enough below condenser 124 to provide a balancing leg of oil in line 134.

The temperatures and other detailed operating conditions hereinabove given are to be understood merely as indicative of good practice in handling typical topped crudes such, for example, as *Urania* (Louisiana) and *Columbia* (South America) crudes. Obviously such operating conditions will vary to some extent with the type of crude charging material, and hence the operating data are to be regarded as given for purposes of illustration and not as rigidly restrictive.

It is very important to rigidly exclude access of air into the distilling system, since the occurrence of even very slight oxidation makes it impossible to produce directly, as overhead distillates, finished lubricating oil products of the character here in question. All seams and joints exposed to temperature changes should be welded, and the entire system should be made absolutely tight.

By a stable lubricating oil, as the expression is herein employed, is meant one that does not undergo changes in storage and use which are in the nature of breakdown or decomposition and which are recognized by the industry as characterizing inferior lubricating oils. A lubricating oil which, upon being heated to 300° F. and being held at this temperature for 10 minutes, does not darken in color more than one-half point on the standard Saybolt color scale, does not acquire a bluish cast in place of the desired greenish bloom, and, does not have or develop an unpleasant odor, is a stable oil.

What is claimed is:

1. In a process of manufacturing lubricating oil, wherein lubricating oil components of a charge of suitable mineral oil are distilled off while the charge is being circulated in a closed path or circuit which includes a tube or pipe-still heater, a vaporizer and the necessary connecting conduits for delivery of oil from the heater to the vaporizer and for return of oil therefrom to the heater, respectively, the method of re-charging such circuit, after a given charge has been distilled down to residue, which comprises discontinuing delivery of the circulating residue to said vaporizer and discharging it from said delivery conduit to a point outside the circuit while continuing to withdraw residue from said

vaporizer and to pass it through said heater, and then, when substantially all or most of the residue has been withdrawn from said vaporizer, introducing a fresh charge of mineral oil into the circuit at a point in said return conduit in order to force any remaining residue through said heater and into said delivery conduit for discharge therefrom, resuming delivery of oil to said vaporizer when substantially all the residue has been thus discharged from the circuit, and continuing introduction of fresh charge until the circuit is fully re-charged, whereby the circuit may be re-charged in a relatively short time while minimizing heat losses and without endangering the heater tubes through overheating.

15 2. The method as defined in claim 1 which fur-

ther includes reducing the speed of oil flow in the circuit while the residue is being discharged therefrom and the first portion of the fresh charge is being introduced.

3. The method as defined in claim 1 which further includes maintaining a low absolute pressure in the circuit during the distilling and recharging operations.

4. The method as defined in claim 1 which further includes maintaining an absolute pressure of about 6 millimeters of mercury in the vaporizer during the distilling operation and preventing any substantial increase in pressure in the circuit during the recharging operation.
